UNITED STATES PATENT OFFICE.

WALTER IDELL AND HANNS MENDELSOHN, OF BERLIN, GERMANY; SAID MENDELSOHN
ASSIGNOR TO SAID IDELL.

COMB.

Application filed January 22, 1925. Serial No. 4,004.

To all whom it may concern:

Be it known that we, WALTER IDELL and HANNS MENDELSOHN, citizens of Germany, residing at Berlin, Germany, have invented 5 certain new and useful Improvements in Combs, of which the following is a specification.

Our invention refers to combs and more especially to foldable pocket combs. It is 10 an object of our invention to provide a foldable comb the parts of which can be locked in unfolded position more easily and safely than similar combs hitherto designed, in which slides embracing the back of the comb 15 were employed for preventing the parts from folding.

In the drawings affixed to this specification and forming part thereof a foldable comb embodying our invention is illustrated 20 by way of example. In the drawings—

Fig. 1 is an elevation showing the comb in unfolded condition,

Fig. 2 is a cross-section on the line A—A in Fig. 1,

25 Figs. 3 and 4 are longitudinal sections on the lines B—B and C—C, respectively in Fig. 1,

Figs. 5 and 6 are similar views showing the comb in folded condition, and

30 Fig. 7 is an elevation of a modification.

Referring first to Figs. 1-6, the comb is formed of three sections, two end sections 1 and 3 and a middle section 2 hinged together by means of sheet metal fittings 35 4, 5, 6 bent into U-shape, each fitting embr-

35 aching the back of a section and being connected with it by rivets, but leaving guide channels 7, 8, 9, respectively between the back of the sections and the respective 40 fitting, these guide channels being disposed in line when the comb is unfolded. Contiguous ends of the fittings 4, 5, 6 are formed into hinges 10, 11 which serve for joining the sections together. In the guide channels

45 there are mounted for longitudinal displacement three locking bars 12, 13, 14 connected by links 15 and 16 inserted in their slotted ends. The middle bar 13 is equal in length to the middle section 2. A knob 17 mounted

50 on the end bar 14 projects from a slot 18 in the back part of the fitting 5. Slots 19, 20 in the adjoining ends of the fittings receive the links 15, 16, when the comb is folded.

55 When the comb is unfolded, the locking

bars 12, 13, 14 are shifted to the right by pulling the knob 17, whereby the links 15, 16 are brought out of register with the joints between the sections 1, 2, 3, which are thus locked against refolding by the bars 12, 13, 60 14. Thus the operation of the knob 17 suffices to lock and unlock the parts.

The modification shown in Fig. 7, while in all other details identical with the one described with reference to Figs. 1-6, differs therefrom in that only two locking bars 13' and 14' are provided, one of which equals in length the middle section 2 and, on being shifted in the direction of section 3, bridges the joint between sections 2 and 70 3 and thereby locks same in unfolded position.

By combining springs (not shown) with the hinges connecting the single sections the comb will unfold of itself in a well known 75 manner.

Obviously more and less than three sections can be united together.

We wish it to be understood that we do not desire to be limited to the exact 80 details of construction shown and described, for obvious modifications will occur to a person skilled in the art.

We claim:—

1. A foldable comb comprising a plurality of juxtaposed sections hinged together and having guide channels provided on their backs and a plurality of locking bars linked together and displaceable in said channels. 85

2. A foldable comb comprising a plurality of juxtaposed sections hinged together and having guide channels provided on their backs and a plurality of locking bars linked together and displaceable in said 90 channels, the bar hinges and the section hinges being equally distanced apart.

3. A foldable comb comprising a plurality of juxtaposed sections hinged together and having guide channels provided on their backs and a plurality of locking bars linked together and displaceable in said 100 channels, one of said bars being equal in length to one of said sections.

4. A foldable comb comprising a plurality of juxtaposed sections hinged together and having guide channels provided on their backs and a pair of locking bars linked together and displaceable in said channels. 105

5. A foldable comb comprising a plu- 110

- rality of juxtaposed sections hinged together and having guide channels provided on their backs, a plurality of lockings bars linked together and displaceable in said channels and means projecting from said channels for displacing said bars.
6. A foldable comb comprising a plurality of juxtaposed sections, U-shaped fittings mounted on the backs of said sections so as to form guide channels thereon and a plurality of locking bars linked together and displaceable in said channels.

7. A foldable comb comprising a plurality of juxtaposed sections, U-shaped fittings mounted on the backs of said sections 15 so as to form guide channels thereon, said fittings being hinged together and a plurality of locking bars linked together and displaceable in said channels.

In testimony whereof we affix our signatures.

WALTER IDELL.
HANNS MENDELSON.
